UNITED STATES PATENT OFFICE.

GEORGE CASSADY, OF FLINT, MICHIGAN.

FEED-WATER HEATER.

SPECIFICATION forming part of Letters Patent No. 274,561, dated March 27, 1883.

Application filed November 14, 1882. (No model.)

To all whom it may concern:

Be it known that I, GEORGE CASSADY, a citizen of the United States, residing at Flint, in the county of Genesee and State of Michigan, have invented a new and useful Feed-Water Heater, of which the following is a specification, reference being had to the accompanying drawings.

This invention relates to feed-water heaters for locomotive and other boilers; and it consists in certain improvements in the construction of the same, which will be hereinafter fully described, and particularly pointed out in the claims.

15 In the drawings hereto annexed, Figure 1 is a top view, showing my invention applied to the fire-box of a locomotive, the crown-sheet having been broken away in order to show the invention more clearly; and Fig. 2, 20 is a transverse sectional view on the line *x x*.

Corresponding parts in the several figures are denoted by like letters of reference.

A A represent the side walls, B the back wall, and C the front, of the furnace, having the door D.

25 E is a pipe extending transversely through the furnace, near its rear end, a short distance below the crown-sheet F, and having its outer ends connected with vertical cylindrical chambers G G, which are supported outside the side walls of the furnace by said pipe E. The upper ends of the chambers G are connected by pipes H with the steam-dome I of the boiler. Their lower ends are connected by pipes J 35 with the injectors.

The pipe E is provided with a centrally-located partition, K, at the sides of which forwardly-extending pipes L L are connected to said pipe E. The pipes L L are coiled outwardly, as shown, in zigzag parallel courses, and in a horizontal plane a short distance below the crown-sheet, until they finally extend out through the front of the furnace, as at M, and thence downward and into the boiler. 40 The several bends of the pipes L at the front end of the furnace are provided with wash-out plugs N.

In operation water is pumped into the chamber G through the pipes J. Check-valves O, 50 contained in said chambers, instantly close the pipes H, thus forcing the feed-water to

enter the feed-pipes L, which, as will be seen, are thoroughly exposed to the furnace-fire, and, being below the crown-sheet, are entirely enveloped by the flames. The water during 55 its passage through the feed-pipes is thus thoroughly heated or partially converted into steam, and is in this state delivered into the boiler. When the pumping is suspended the check-valves O close the pipes J, thus permitting the pipes L to communicate through the chambers G and pipes H with the steam-dome, into which steam generated in the pipes L is thus conducted.

It will be understood that the injectors may 65 be operated simultaneously or independently, as may be desired, the pipes L L being separated by the partition L. Therefore any accident to either side of the feed-water apparatus will not incapacitate the other side for work. 70

I claim and desire to secure by Letters Patent of the United States—

1. The combination, with a boiler-furnace, of a transverse horizontal pipe having a central partition, pipes connected to said transverse pipe at the sides of said partition, coiled in a horizontal plane below the crown-sheet and leading to the boiler, chambers at the outer ends of the said transverse pipes, pipes connecting the said chambers with the steam-dome of the boiler and with the injectors, and double-acting check-valves contained in said chambers, as set forth.

2. As an improvement in feed-water heaters, the combination, with a boiler-furnace, of 85 a feed-pipe coiled in said furnace below the crown-sheet, and having one end connected with the boiler and the other end with both the steam-dome and the injector, and an automatic double-acting check-valve so arranged 90 as to cut off communication between the feed-pipe and the steam-dome while the injector is being operated, and to close the injector-pipe when pumping is suspended, as set forth.

In testimony that I claim the foregoing as 95 my own I have hereto affixed my signature in presence of two witnesses.

GEORGE CASSADY.
